CLAIM

I claim, the ornamental design for a sole for shoe, as shown and described.

DESCRIPTION

FIG. 1 is a perspective view of a sole for shoe, showing my new design;

FIG. 2 is a bottom plan view thereof;

FIG. 3 is a top plan view thereof;

FIG. 4 is a side view thereof;

FIG. 5 is an opposite side view thereof;

FIG. 6 is a front view thereof; and,

FIG. 7 is a bottom view thereof.

The broken lines show portions of the sole, as well as environment in the form of a shoe upper, none of which form a part of the claimed design.
